UNITED STATES PATENT OFFICE.

GEORGE COOK, OF ALLENDALE, NEW JERSEY, ASSIGNOR TO AMERICAN BRAKE SHOE & FOUNDRY COMPANY, OF MAHWAH, NEW JERSEY, A CORPORATION OF NEW JERSEY.

BACK FOR BRAKE-SHOES.

1,074,352.

Specification of Letters Patent.

Patented Sept. 30, 1913.

Application filed May 17, 1913. Serial No. 768,199.

To all whom it may concern:

Be it known that I, GEORGE COOK, a citizen of the United States, and a resident of Allendale, in the county of Bergen and State 5 of New Jersey, have made and invented certain new and useful Improvements in Backs for Brake-Shoes, of which the following is a specification.

My invention relates to an improvement 10 in brake shoes, and more particularly to that type thereof usually known and referred to as a "steel back" shoe, that is, a shoe wherein is employed a back formed of steel or wrought metal and located at or adjacent to 15 the rear surface of the body of the shoe, the object of the invention being to provide a shoe of this type with a removable or detachable end so arranged with relation to the steel back as to be locked or secured 20 against movement thereon.

A further object of the invention is to secure the detachable ends to the back against movement thereon by means integral with the back itself or integral with the detachable 25 ends, in order to prevent the employment of separate or additional parts, and with these and other objects in view, the invention consists in certain novel features of construction and combination of parts as will be 30 hereinafter fully described and pointed out in the claims.

In the accompanying drawings, Figure 1 is a view in perspective of a back for a brake shoe constructed in accordance with my invention. Fig. 2 is a sectional view of one 35 end thereof. Fig. 3 is a view in perspective of a portion of a back provided with a modified form of my invention, and Fig. 4 a sectional view thereof. Fig. 5 shows one end 40 of a back slotted in a certain way to receive and hold a detachable end, and Fig. 6 a sectional view of the same showing the detachable end applied to the same. Fig. 7 is a sectional view of another modified form of 45 back showing the detachable end secured in place against movement. Figs. 8 and 9 are sectional views of several other modified forms of my invention.

Referring to the drawings, 10 represents 50 the back for a brake shoe, usually termed a "steel back", and formed from steel or wrought metal, and, as usual, is provided about midway its length with a key lug 11 for the purpose of attaching the completed shoe 55 to a brake head, the back being formed of

the two side pieces 12—12, and central portions or anchors 13, which, in the form as illustrated in the present drawing, are made integral with the key lug 11. The extreme ends of the back are bent upwardly to provide end stops 14—14, against which the extreme ends of the brake head (not shown) abut or fit. Detachably secured to this back are the removable ends 15—15, formed, for instance, by stamping or pressing the same 60 out of sheet metal, as illustrated in several figures of the drawings, or formed of cast metal, as illustrated in Fig. 9, each of these detachable ends being provided, generally speaking, with a hook or lug passing up 65 through an opening in the back of the shoe whereby to removably secure it thereto. In shoes utilizing detachable ends, the body 16, Fig. 9, is preferably made of any of the well-known compositions, in contradistinction to 70 the usual cast metal body, the detachable ends being first properly assembled with the back 10, and the composition body then pressed or anchored to the back and between the ends 15. To insure the detachable ends 75 against movement on the back, which might tend to injure or destroy the extreme ends of the composition body, I lock them to the back 10, preferably by means formed integral either with the back itself or integral 80 with the detachable ends.

In Figs. 1 and 2 I have shown one of the detachable ends 15 provided on its upper side with the elongation 17, slightly bent or curved upwardly at its extreme end as illustrated at 18, this portion of the end being 85 sufficiently long to contact with the central portion or anchor 13 of the back, thus holding the end 15 tightly in place and avoiding all danger of said end moving longitudinally on the back.

In Figs. 3 and 4 I have illustrated the locking means formed integral with the back itself, these means comprising the arm 19 formed integral with the end stop 14, the 90 extreme end 20 being bent over and upon the hook or lug 21 forming a part of the end stop 15, thus holding the latter tightly in position and against movement on the back. Instead, however, of forming the locking 95 means integral with the end stop, I may form them integral with the sides 12, as illustrated in Figs. 5 and 6, these sides being slotted, as illustrated at 22 and 23, and slightly bent upwardly as illustrated in sec-

tion in Fig. 6 to bear against the hook portion 21 of the end stop 15.

Again, as illustrated in Fig. 7, the hook portion 24 of the end stop 15 may be bent 5 into an extra fold 25, and the extreme end 26 thereof bent downwardly to overlap or lock against the end stop 14, the detachable end being thus locked against movement with relation to the back.

10 Again, as illustrated in section in Fig. 8, the central portion or anchor 13 may be extended, and slightly bent upwardly, as illustrated at 27, to bear against the hook portion 21 of the stop 15, the same being true 15 of the structure illustrated in Fig. 9, wherein in the removable or detachable end 28 is formed of cast metal, the central portion or anchor 13 of the back being slightly bent up at its extreme end to bear against the detachable end 28 and thus hold it in position 20 against movement on the back.

In all of the above instances it will be noted that the detachable or removable end 25 is locked or secured against any longitudinal movement on the back, the locking means being preferably formed integral either with the back or with the removable end.

It will be understood, of course, that I do not limit my invention to integral means for 30 locking the ends, nor do I intend to limit it to any particular form or construction of locking means, as other and various structures will suggest themselves to those skilled in the art whereby to accomplish the same 35 purpose, my claim being intended to cover broadly any and all locking means whereby to hold or secure in place, and against movement, a detachable or removable end upon a brake shoe steel back, whereby to prevent 40 injury to the ends of the composition body anchored to the back and between the removable ends. Nor do I intend to limit the invention to any particular form of back or key lug, as such may be varied in structure 45 as desired.

What I claim is:—

1. A back for a brake shoe provided with detachable ends, and means for securing said ends against movement on said back when 50 assembled therewith.

2. A back for a brake shoe comprising a back proper and detachable ends, and means

formed integral therewith for locking said ends in place on said back against movement thereon. 55

3. A back for a brake shoe comprising a back proper and removable ends attached thereto, in combination with means formed integral with said detachable ends for locking the latter against movement on said back 60 when assembled therewith.

4. A back for a brake shoe comprising a back proper and detachable ends secured thereto, portions of said back proper impinging against said detachable ends whereby to prevent movement of the latter on said back proper. 65

5. A back for a brake shoe comprising two elements, viz., a back proper and detachable ends secured thereto, one of said 70 elements being elongated to impinge against the other whereby to prevent movement of said detachable ends on said back proper.

6. A back for a brake shoe comprising a back proper formed with central anchors 75 and with openings near the ends thereof, removable ends extending through said openings, said central anchors impinging against said removable ends whereby to hold the latter against movement on the back when assembled therewith. 80

7. A back for a brake shoe comprising a back proper formed with openings near its ends, removable ends formed with hooks, said hooks extending through the openings 85 in said back, and means connected with said back for impinging against said hooks for holding said removable ends against movement on the back when assembled therewith.

8. A back for a brake shoe comprising a 90 back proper provided with a key lug, of removable ends secured to said back, and means formed integral with said lug for impinging against said removable ends to hold the latter against movement on the back 95 when assembled therewith.

Signed at New York, borough of Manhattan, in the county of New York, and State of New York, this 15th day of May, A. D. 1913.

GEORGE COOK.
